FLIER FOR SPINNING MACHINES

Harvey E. Herr, Buffalo, N. Y., assignor to Herr Manufacturing Company, Inc., Buffalo, N. Y., a corporation of New York

Application September 20, 1939, Serial No. 295,794

6 Claims. (Cl. 57—116)

This invention relates to certain new and useful improvements in the fliers employed in connection with spinning machines.

It has for one of its objects to so design and construct the flier as to readily effect the counter-balancing of the flier wire or wires carried thereby and thereby produce an evenly and sensitively balanced flier which reduces the thread tension to a minimum.

Another object of the invention is to provide a light weight, counter-balanced flier wherein different sized weights are provided for detachable connection to the flier body, together with simple and effective means for detachably connecting or coupling the weight to the flier body so as to enable them to be readily applied and removed.

In the accompanying drawing:

Figure 1 is a fragmentary side elevation of a bobbin and spindle showing the improved counter-balanced flier operatively associated therewith. Figure 2 is an enlarged vertical section of the flier with the remaining associated parts shown in elevation. Figure 3 is a top plan view of the flier. Figure 4 is a perspective view of the flier body or base. Figure 5 is an inverted perspective view of one of the detachable counter weights.

Similar characters of reference indicate corresponding parts throughout the several views.

Referring now to the drawing, 10 indicates a spindle and 11 a bobbin mounted thereon. The flier which is detachably mounted on the spindle may be of any appropriate construction, that shown in the drawing by way of example consisting of an anchoring sleeve or journal 12 for attachment to the tapered end of the spindle, and a hub 13 rotatably mounted on the journal and carrying a wire base or body 14 to which the flier wire 15 is attached. As shown in Figures 2 and 3, the flier wire is applied to one side of the flier body and is retained in place by a loop 16 formed in the body, a rotatable clamping ring 17 applied to the hub serving to securely hold or clamp the wire against displacement relative to the retaining loop.

The flier body, at that side thereof diametrically opposite the wire attaching portion thereof, is provided with an arm 18 to which a weight 19 is adapted to be detachably applied for counter-balancing the weight of the flier wire, different-sized weights being employed depending upon the flier wire or wires used and the conditions of such use. This weight element is preferably in the form of a thin plate adapted to rest flatwise on the arm 18, the latter and the weight having complementary means for retaining the weight in its

operative position on the flier. By preference, the weight is disposed radially between the flier hub 13 and the outer edge of the arm 18, the latter being provided at such edge with an upturned lug or retaining lip 20 and inwardly thereof with an opening 21, while the weight 19 has complementary interlocking means consisting of a notch 22 formed in its outer edge for coupling engagement with the arm-lug 20, and a teat 23 for engagement with the arm-opening 21. These complementary interlocking devices retain the weight effectually against displacement in directions radially, laterally and vertically relatively to the arm 18, and at the same time permit its ready application and removal to and from the flier body. For the purpose of further retaining the inner marginal edge of the weight against vertical displacement, the same may be engaged with the clamping ring 17 in the manner shown in Figures 2 and 3.

The flier body including the weight-supporting arm 18 is made of comparatively thin, light material, such as aluminum, and the detachable weight elements 19 are made of a light, thin material so that the flier as a whole is light in weight and when balanced by the proper weight for counter-balancing the flier wire it operates smoothly and with a minimum of tension on the threads during the spinning operation.

I claim as my invention:

1. A flier, comprising a body having a flier wire projecting from one side thereof and an arm at the diametrically opposite side thereof, a counter-balancing weight detachably mounted on said arm, and complementary male and female interlocking means applied to the arm and the weight, respectively, for resisting displacement of the latter in directions radially, laterally and vertically relatively to said arm, the interlocking elements on the arm being disposed in spaced relation at different distances from the axis of the flier-body. 30

2. A flier, comprising a body having a flier wire projecting from one side thereof and an arm at the diametrically opposite side thereof having a plurality of coupling elements thereon disposed in spaced relation radially thereof, and a substantially flat member for counter-balancing the weight of the flier wire detachably mounted flatwise on said arm and having coupling elements at its inner and outer ends engageable with and complementary to the arm coupling elements. 45

3. A flier, comprising a body having a flier wire projecting from one side thereof and an arm at the diametrically opposite side thereof having substantially laterally and vertically extending coupling elements thereon, and a counterweight for 50

55

- the flier wire detachably mounted on said arm and consisting of a flat plate having complementary laterally and vertically extending coupling elements thereon engageable with those of said arm.
4. A flier, comprising a body having a flier wire projecting from one side thereof and an arm at the diametrically opposite side thereof having a coupling lug at one edge and an opening disposed inwardly thereof, and a substantially flat member for counter-balancing the weight of the flier wire detachably mounted on said arm and having a complementary notch and seat therein engageable with said arm-lug and opening, respectively.
5. A flier, comprising a body having a flier wire projecting from one side thereof and an arm at its

diametrically opposite side having a coupling lug at its outer edge and an opening disposed inwardly thereof, a counter-weight for the flier wire detachably mounted flatwise on said arm and consisting of a thin plate having a notch at its outer edge engageable with said arm-lug and a seat inwardly thereof engageable with said arm-opening, and means on said body for clamping the flier wire thereto and having a portion engageable with the inner edge of said plate for clamping the latter to said arm.

6. A counter-balancing element for fliers, comprising a substantially flat member having a notch at one end thereof and a seat adjacent its opposite end.
